UNITED STATES PATENT OFFICE.

WESLEY C. LOUCKS AND CHARLES W. DERRICK, OF AVOCA, NEW YORK.

WAGON-JACK.

SPECIFICATION forming part of Letters Patent No. 373,189, dated November 15, 1887.

Application filed September 3, 1887. Serial No. 248,742. (No model.)

To all whom it may concern:

Be it known that we, WESLEY C. LOUCKS and CHARLES W. DERRICK, citizens of the United States, residing at Avoca, in the county 5 of Steuben and State of New York, have invented a new and useful Improvement in Carriage and Wagon Jacks, of which the following is a specification.

Our invention relates to improvements in carriage and wagon jacks; and it consists in certain novel features, hereinafter described and claimed.

In the accompanying drawings, which fully illustrate our invention, Figure 1 is a side elevation of our improved jack, showing it in its lowered position; and Fig. 2 is a similar view, looking at the opposite side, showing it as supporting the vehicle-axle in an elevated position.

Referring to the drawings by letter, A designates the leg or standard, and B the lifting-bar. The lifting-bar B is provided at its upper end with a series of notches, C, in which the axle of the carriage or wagon is held while being cleaned or lubricated.

D designates a brace which has one end pivotally secured to the leg and its other end pivotally secured to the lifting-bar, as clearly shown.

E designates a link having its opposite ends pivotally secured to the upper ends of the leg A and the lifting-bar, and the operating-lever F is pivotally mounted upon the same bolts, G H, that secure the link. The operating-lever 35 is thus pivotally secured to both the lifting-bar and the standard or leg on the side opposite the link E. The standard is thus brought into the same plane with the lifting-bar, which is provided on its under edge, near its top, with the notch I, and when the lever F is depressed the upper end of the standard is thrown into this notch I, as clearly shown.

The operation of the jack will, it is thought, be readily understood. When the operating-lever 45 is elevated, as shown in Fig. 1, the stand-

ard and the lifting-bar will be drawn from each other and the lifting-bar lowered. When the device is in use, the axle of the carriage or wagon is rested in one of the notches C in the upper or outer edge of the lifting-bar, and the lever is then depressed. As the lever is forced downward, the upper end of the lifting-bar is raised, thereby lifting the wheel of the vehicle from the ground, when it can be readily removed from the axle and the same cleaned or 55 lubricated. When the upper end of the lifting-bar is raised, the upper end of the standard is simultaneously thrown downward and toward the lifting-bar and into engagement with the notch I, thereby, in connection with the brace E, firmly supporting the lifting-bar and preventing the spreading of the jack.

It will be seen that our device is very simple in construction and operation, and can be manufactured at a small cost.

Having thus described our invention, what we claim, and desire to secure by Letters Patent, is—

The improved carriage and wagon jack herein described and shown, comprising the 70 leg or standard A, the lifting-bar B, having a series of notches, C, in its upper edge to receive the vehicle-axle, and a notch, I, in its lower edge to receive the upper end of the standard, the link E, pivoted at its opposite 75 ends to the lifting-bar and to the standard by means of the bolts G H, the operating-lever F, pivotally mounted upon said bolts G H, and the brace D, having its opposite ends pivoted, respectively, to the standard and the lifting-bar, substantially as specified.

In testimony that we claim the foregoing as our own we have hereto affixed our signatures in presence of two witnesses.

WESLEY C. LOUCKS.
CHARLES W. DERRICK.
